UNITED STATES PATENT OFFICE.

WILLIAM CHARLES BRISSE, OF DETROIT, MICHIGAN.

DESIGN FOR AN ELECTRIC FLOOR-LAMP.

54,721.

Specification for Design.

Patented Mar. 23, 1920.

Application filed October 25, 1919. Serial No. 333,407. Term of patent 14 years.

To all whom it may concern:

Be it known that I, WILLIAM C. BRISSE, a citizen of the United States, residing at Detroit, in the county of Wayne and State of Michigan, have invented a new, original, and ornamental Design for an Electric Floor-Lamp, of which the following is a specification, reference being had to the accompanying drawing, forming part thereof.

The figure is a side elevation of an electric floor lamp, showing my new design.

I claim:

The ornamental design for an electric floor lamp, as shown.

WILLIAM CHARLES BRISSE.
